UNITED STATES PATENT OFFICE.

ALBERT WHITE, OF LOWELL, MASSACHUSETTS, ASSIGNOR, BY MESNE ASSIGNMENTS, TO THE COLUMBIA CASH REGISTER COMPANY, OF PORTLAND, MAINE.

INDICATING MECHANISM FOR CASH-REGISTERS.

SPECIFICATION forming part of Letters Patent No. 558,887, dated April 21, 1896.

Application filed August 14, 1895. Serial No. 559,269. (No model.)

To all whom it may concern:

Be it known that I, ALBERT WHITE, a citizen of the United States, residing at Lowell, in the county of Middlesex and Commonwealth of Massachusetts, have invented a certain new and useful Improvement in Cash-Indicators, of which the following is a specification.

My invention relates to cash-indicators; and it consists in the devices and combinations hereinafter described and claimed, comprising means whereby the different tablets necessary to the indication of the amount of a single transaction may be displayed successively instead of simultaneously and without causing the previously-displayed tablets of the same indication to disappear, while at the same time the raising of any tablet will cause all the displayed tablets of a previous indication to disappear.

In the accompanying drawings, Figure 1 is a vertical section on the line 1 1 in Fig. 2 of the tablet-rod guides, the rods which serve as fulcrums for the keys, racks, and rack-dogs, the movable locking-plate and front cam-plate formed in one piece with each other, and the stationary rear cam-plate, showing in side elevation a side of the frame, keys, racks, rack-dogs, tablets, tablet-carrying rods, tablet-actuating rods, locking-plate spring, and sliding pins provided with heads; Fig. 2, a front elevation of the tablets, their carrying and actuating rods provided with sliding pins, a part of the frame, including the tablet-rod guides, the locking-plate and its spring, and some keys in vertical cross-section on the line 2 2 in Fig. 1, the guides and locking-plate being broken, and said Fig. 2 representing parts of three sections of an indicator, Figs. 3 and 4 representing modifications of the locking-plate; Fig. 3, a front elevation of a locking-plate and front cam-plate formed in separate parts, the rear cam-plate, stop-plates, part of the frame, including the tablet-rod guides, and a leaf-spring to restore said locking-plate; Fig. 4, a vertical section on the line 4 4 in Fig. 3 of said guides and plates, a side elevation of the spring shown in Fig. 3, and of tablet-carrying and tablet-actuating rods with headless pins; Fig. 5, a vertical sec-

tion of the locking-plate, cam-plates, guides, tablet-carrying and tablet-actuating rods, and swinging hooks instead of the pins shown in Fig. 1; Fig. 6, a vertical section of the guides, tablet-carrying and tablet-actuating rods, locking-plate, and the front cam-plate, the rear cam-plate being omitted and the pins being held against the front cam-plate by springs on said rods, the sections in Figs. 1, 4, 5, and 6 being at right angles to the locking-plate.

A denotes the frame of the indicator; a a', horizontal cross-pieces, which form a part of said frame and serve to guide vertically the tablet-carrying-rod B; b, indicating-tablets bearing words or numbers corresponding to words or numbers on the keys C, said keys C turning on a horizontal fulcrum-rod c, supported in frame A, these parts being all of common construction except as hereinafter stated.

Any usual means of preventing each key from commencing its return stroke before its operative stroke is completed may be used.

In Figs. 1 and 2 the rear ends of the keys C are represented as provided each with a single tooth c', adapted to engage the teeth d of a curved rack D, pivoted at its upper end at d' to the frame A in such a manner that the teeth d are normally held by the weight of said rack in engagement with the tooth c' or rear end of the corresponding key, and the teeth d of each rack D are hooked upward in such a manner that a partially-operated key is prevented from returning to its normal position until the tooth c' of the key has passed all the teeth of the rack D, there being a rack D to each series of keys or section of the machine, and usually three such sections in a machine, indicating, respectively, dollars, dimes, and cents. When the tooth c' of a key has passed over a rack, said tooth strikes an incline d², which throws said rack backward and beyond the rear end of a lever or dog E, pivoted at e on the frame A, which rear end, (the front end of said lever,) being weighted for that purpose at e', then rises in front of the lower end of said rack and holds the same out of engagement until said key at the completion of its return movement strikes and depresses said rear end 95 100

of said dog E and allows said rack to swing forward.

Usually each tablet-carrying rod rests directly upon the rear arm of a pivoted key, like that shown in the drawings, or upon the rear arm of a lever worked by a slide, as shown in the Patent No. 480,698, granted August 9, 1892, to Jacques, and is raised by the depression of the front arm of said key or lever, and each tablet-carrying rod commonly has a shoulder, detent, or projection adapted and arranged in rising to strike and push aside a swinging or sliding locking-bar, which is immediately after drawn by a spring under said shoulder and holds up said tablet-rod until the locking-bar is again pushed aside by the shoulder of another rising tablet-rod. If the tablet-rods and their shoulders and the locking-bar are made with very great accuracy, the raising of one tablet will cause any previously-raised tablet-rod to fall, but only while the parts are new and unworn, or equally worn, for as soon as one shoulder is worn a trifle more than the others it will be too short to move the locking-bar sufficiently to release a previously-raised tablet-rod. Where two or more tablet-rods are raised at one indication and their shoulders are supported upon the locking-bar, and it is desired to display only the tablet carried by one of them at the next indication, it is evident that the depression of the corresponding key can have no effect on the locking-rod without the use of other mechanism than the previously-raised tablet-rod. It is therefore customary to use a mechanism operated by any key to move aside the locking-bar to allow the displayed tablets to fall. I avoid the necessity for any such tablet-releasing mechanism common to all the keys by making two tablet-rods to each key C and tablet, one rod, B, Figs. 1 and 2, to which the tablet b is secured, as above stated, in the usual manner, and another rod, B', which preferably raises the rod B and moves the locking-bar or locking-plate F to allow the displayed tablets to fall.

Each rod B B' is provided with a pin b² b³, sliding horizontally in a hole formed in such rod from front to back of the same and longer than the thickness of such rod, so that each pin at all times projects from the front or back of the corresponding rod, and each pin b² b³ is preferably provided with an enlarged head b⁴ b⁵ to limit the forward movement of said pin, the rods B B' being arranged side by side in pairs and the rod B' having preferably a lateral projection b', on which said rod B rests while being raised and when the tablet is undisplayed and the rod B' resting directly upon the rear arm of the lever or key C.

By making the rear end portion of the key broad enough, as shown at D' in Fig. 2, the rods B B' may both normally rest upon the key, and the projection b' may be dispensed with, the rod B being in this case increased in length by the distance from the top of a

projection b' to the lower end of the corresponding rod B'.

The locking-plate F is represented in Figs. 70 1 and 2 as formed in one piece with the front cam-plate G, the latter being convex vertically on its rear surface and straight horizontally, as shown in Fig. 1, and the locking-plate above said plate G having backwardly 75 extending fingers f and below said plate G having other downwardly-extending vertical fingers f', having lateral inclines f². The ends of the fingers f and the greatest backward projection of the cam-plate G and the 80 rear faces of the vertical fingers f' lie in about the same vertical plane and in close proximity to the tablet-rods. Ears f³ f⁴ on the locking-plate F loosely surround guide-rods f⁵ f⁶, supported horizontally in the frame 85 A or in plates a² a³, secured by bolts or screws a⁴ a⁵ to said frame to enable said locking-plate to have an endwise motion on said guide-rods in one direction, when the pins b³ in rising strike against the inclines f² and, subsequently, in the other direction, by the contraction of the spring f⁷, stretched between the frame or the plate a³ and a hook g, secured on said front cam-plate G.

A stationary rear cam-plate G' is secured 95 to the frame of the machine and extends back of all the tablet-rods and has a central vertical portion g' and upper and lower portions g² g³, which are bent or inclined from said central portion, as shown in Fig. 1, toward 100 the tablet-rods, the upper portions g² serving to crowd the pins b³ forward at the last part of the upward movement of the rods B and the lower incline g³ pushing the pins b³ forward in the last part of the descent of the 105 rods B'.

When the front end of any key is depressed, the two corresponding rods B B' are raised. The pin b³ of the rod B' (said pin b³ at the beginning of the operative stroke of the key 110 having its greatest forward projection) strikes the corresponding incline f² and moves the locking-plate F endwise, (to the left in Fig. 2,) and rising above said incline f² allows said locking-plate to be returned to normal position by the spring f⁷. The depression of the key also carries the pin b² of the rod B above said locking-plate, the action of the upper incline g² on the head b⁴ or rear end of said pin b² crowding the front end of said pin b² forward over the corresponding finger f, so that when the key is let go said pin b² rests upon the top of said finger f.

When it is desired to make another indication, another key is depressed and the endwise movement of the locking-plate carries the finger f out from under the pin b² of the previously-raised tablet-rod, allowing the same to fall during the first part of the depression of the second key, said pin b² being 125 thrown backward by striking the front cam-plate G in its descent. The front cam-plate G also moves the pin b³ backward when the latter has risen above the finger f' and pre-

vents said last-named pin when descending from catching on the top or side of the finger f' . The lower incline g^3 of the rear cam-plate G throws the pin b^3 forward when the rod B' 5 falls to its lowest position.

When it is desired to raise more than one tablet for a single indication, the corresponding keys may be simultaneously operated in the usual manner, or when, owing to the distance apart of said keys, it is impossible to do this with one hand and only one hand is at liberty a key in each of two sections of the machine may be depressed one at a time or simultaneously, not fully, but until the pins b^3 15 of the corresponding rod B' have risen above the fingers f' of the locking-plate, and a key in the third section may then be fully depressed and let go, after which the operation of the first two keys, one at a time or both 20 together, may be completed without moving the locking-plate and without dropping the fully-raised tablet of the same indication. (See the two partially-raised tablets and the one fully-raised tablet in Fig. 2.)

25 Inasmuch as the first part of the movement of the key causes the locking-plate to release previously-raised tablets, it follows that a depression of the key corresponding to a raised tablet first drops and then raises again said 30 tablet, and that where it is desired to raise only one or two of a larger group of tablets, raised at the next previous indication, the depression of the keys corresponding to the tablets to be a second time raised will release the 35 others.

35 In Figs. 1 and 2 the front cam-plate is made in one with the locking-plate for convenience of construction merely, the endwise movement of said cam-plate serving no useful purpose.

40 In the modified form shown in Figs. 3 and 4 the front cam-plate G is stationary and has flanges g^4 g^5 , by means of which it is secured to the sides of the frame. The pins b^6 b^7 , which 45 serve the same purpose as the pins b^2 b^3 in Figs. 1 and 2, are without heads and are prevented from projecting too far forward by vertical stop-plates H H', secured to the upper and lower guides a a', respectively. The upper 50 and lower inclined parts of the locking-rod proper are secured to each other rigidly by strips f^8 f^9 , and the return movement of the locking-plate is caused by the resilience of a leaf-spring f^{10} instead of by the contraction 55 of the spiral spring f^7 . (Shown in Figs. 1 and 2.)

60 In Fig. 5 swinging T-shaped pieces b^8 b^9 perform the same office as the pins b^2 b^3 , above described, said pieces b^8 b^9 being pivoted at b^{10} b^{11} on the sides of the rods B B' and having slots b^{12} b^{13} , through which pins b^{14} b^{15} are driven into the sides of said rods to limit the forward movement of the heads b^{16} b^{17} of said pieces, the front and rear ends of said heads, 65 respectively, being acted upon by the front and rear cam-plates G G' just as the front ends or points and heads of the pins b^2 b^3 are.

In Fig. 6 the rear cam-plate is omitted, and pins b^2 b^3 , like those shown in Fig. 1, are thrown forward by leaf-springs g^6 g^7 and backward by the front cam-plate G. 70

Except as above stated the devices shown in Figs. 3 to 6 do not differ from corresponding parts in Figs. 1 and 2.

The sliding-pins b^2 b^3 , b^6 b^7 and swinging 75 pieces b^8 b^9 are all detents.

I claim as my invention—

1. The combination of a frame provided with guides, a movable tablet-holder, a series of keys, an equal series of indicating-tablets, 80 and an equal series of pairs of rods, each rod passing through said guides and each pair of rods being arranged to be raised by the operation of a corresponding key, one rod of each pair carrying one of said tablets and 85 adapted to engage said tablet-holder and the other rod of the same pair being adapted to move said tablet-holder and to disengage the same from any previously-raised tablet-carrying rod, as and for the purpose specified. 90

2. The combination of a frame provided with guides, a movable tablet-holder, a series of indicating-tablets, an equal series of keys, and an equal series of pairs of rods, each rod passing through said guides and each pair being 95 operated by one of said keys, one rod of each pair carrying one of said tablets, and provided with a detent to engage said tablet-holder to support its tablet, and the other rod of said pair being adapted to engage said tablet-holder and to move the same out of engagement with the detent of any previously-raised tablet-carrying rod, as and for the purpose specified. 100

3. The combination of a movable tablet-105 holder provided with inclines, as many indicating-tablets as there are inclines an equal number of keys, an equal series of pairs of rods, each pair being operated by one of said keys, one rod of each pair carrying one of 110 said tablets and provided with a detent to engage said tablet-holder to support said tablet, and the other rod of the same pair having a detent, to engage said tablet-holder and move the same out of engagement with the detent 115 of any previously-raised tablet-carrying rod, as and for the purpose specified.

4. The combination of a movable tablet-holder provided with inclines, as many indicating-tablets as there are inclines an equal 120 number of keys, an equal series of pairs of rods, each pair being operated by one of said keys, one rod of each pair carrying one of said tablets, and provided with a movable 125 detent to engage said tablet-holder, and a cam to move the finger f' which carries the detent of any raised tablet-carrying rod into engagement with said holder, the other rod of each pair having a movable detent to engage one of said inclines to move said holder out of engagement with the detent of any previously-raised tablet-carrying rod, as and for the purpose specified. 130

5. The combination of a frame provided

with guides, a movable tablet-holder, a series of keys, an equal series of indicating-tablets, and an equal series of pairs of rods, each rod passing through said guides and one rod of each pair carrying one of said tablets and adapted to be engaged by said tablet-holder and the other rod of said pair being adapted to move said tablet-holder to release any previously-raised tablet-carrying rod and resting directly upon one of said keys and having a projection upon which the other rod of the same pair normally rests, as and for the purpose specified.

6. The combination of a frame provided with guides, a movable tablet-holder, a series of keys, an equal series of indicating-tablets, and an equal series of pairs of rods, each rod passing through said guides and each pair of rods being arranged to be raised by the operation of a corresponding key, one rod of each pair carrying one of said tablets and adapted to engage said tablet-holder and to be held up thereby, and the other rod of the same pair

being adapted to disengage said tablet-holder from any previously-raised tablet-carrying rod and to be restored to position when said key is let go, as and for the purpose specified.

7. The combination of a tablet-holder, tablet-rods having holes, pins or detents sliding in said holes, and a cam adapted to be struck by said pins, to cause said pins to engage said holder, as and for the purpose specified.

8. The combination of a tablet-holder, tablet-rods having holes, pins or detents sliding in said holes, and a cam adapted to be struck by said pins, to cause said pins to be thrown out of engagement with said holder, as and for the purpose specified.

In witness whereof I have signed this specification, in the presence of two attesting witnesses, this 12th day of August, A. D. 1895.

ALBERT WHITE.
